UNITED STATES PATENT OFFICE.

CHARLES J. KLEIN, OF MILWAUKEE, WISCONSIN, ASSIGNOR TO THE CUTLER-HAMMER MFG. CO., OF MILWAUKEE, WISCONSIN, A CORPORATION OF WISCONSIN.

ELECTRIC SWITCH

1,168,005.

Specification of Letters Patent.

Patented Jan. 11, 1916.

Application filed August 14, 1912. Serial No. 715,049.

To all whom it may concern:

Be it known that I, CHARLES J. KLEIN, a citizen of the United States, residing at Milwaukee, in the county of Milwaukee and 5 State of Wisconsin, have invented new and useful Improvements in Electric Switches, of which the following is a full, clear, concise, and exact description, reference being had to the accompanying drawing, forming 10 a part of this specification.

My invention relates to electric switches.

It has among its objects to provide an improved electric switch especially adapted to use in connection with electric lamp sockets. 15 A further object of my invention is to provide an improved and simplified construction and arrangement of conducting and insulating parts for the switch mechanism whereby the terminals of the switch 20 are readily accessible and the device may be very cheaply and compactly made.

Other objects and advantages of my improvement will hereinafter appear.

In order to clearly and fully disclose my 25 invention I have illustrated one embodiment of the same in the accompanying drawing.

Figure 1 shows a central longitudinal sectional view of the switch in position in a lamp socket. Fig. 2 shows a top plan view 30 of the construction shown in Fig. 1, the socket cap being removed. Fig. 3 shows a bottom plan view of the same. Fig. 4 shows a sectional view on line 4—4, Fig. 1. Fig. 5 shows a sectional view on line 5—5, Fig. 4, 35 the casing shell being removed.

The switch mechanism is inclosed in an insulating base, divided horizontally into two parts, 1 and 2, and held together by vertically extending screws 3 and 4. This base 40 is suitably supported in a lamp socket 5, as for instance by laterally extending lugs 6 on the part 1 thereof. The part 2 of the base is provided with flat vertically extending sides, along which extend binding posts 7 and 8 to which the conductors leading to the 45 switch are connected.

The switch mechanism is of the type described and claimed in my copending application, Serial No. 623,903, filed April 28, 50 1911. It includes a push button operated cam member 9 and a rotary contact member

10 pivoted upon a spindle 11. Upon the reciprocation of this cam member the contact member acts to compress a coiled spring 12 55 surrounding the spindle 11. After a pre-

determined movement of the cam member this spring actuates the contact member to make or break the circuit with a quick snap action at resilient stationary contacts 13 and 14 located in recesses 15 and 16, upon opposite sides of part 2 of the base. These stationary contacts 13 and 14 are provided with vertically extending contact surfaces. The non-contacting ends of the same are bent over, as shown in Fig. 5, so that a portion of the same lies parallel with the bottoms of the recesses 15 and 16 at right angles to the contacting surfaces. Screws 17 and 18 are used to fix the same to the bottoms of the recesses. These screws extend through the base 2 to the opposite side thereof. The contact 13 is connected to a resilient center contact 19 by the screw 17. As shown in Fig. 3, this contact is surrounded by an insulating wall 20 and is prevented by a portion of the same from coming in contact with the end of the spindle 11. The other contact 14 is connected through the screw 18 with the binding post 8; the terminal plate 21 for the latter being secured in a recess upon the bottom of the base 2 by said screw and being provided with an upwardly extending portion 22 which carries the binding post.

A threaded conducting shell 23 is fixed to the bottom of the base by means of the screws 3 and 4, the threaded ends of the same being threaded in a clamping conducting plate 24 of substantially crescent shape which is received within the overturned upper end of the shell. This conducting plate 24 is provided with an upwardly extending lug or extension 25 integral therewith, upon which is carried the binding post 7. As illustrated in Fig. 5 the upper end 26 of the threaded shell is bent inward at right angles and snugly fitted between the bottom of the base and the plate 24, being insulated from the base by an insulating washer 27. Both the inturned end of the threaded shell and the washer are provided with suitable cut-away portions to permit the passage of the extension 25 and the wall 20 upon the bottom of the base. As illustrated, the bottom of the base is also provided with recesses 28 into which the ends of the screws 17 and 18 extend.

It is to be noted that in my improved construction the stationary contacts for the switch mechanism are directly connected to one of the binding posts and the center con-

tact of the device. The threaded conducting shell is also directly connected to the other binding post of the device. This threaded shell is held in position by the same means that hold the parts of the base together. Further, both of the binding posts are located upon the flat sides of the base so that they are readily accessible. It is further to be noted that all of the current carrying parts are carried on the lower insulating base which is of a construction which may be readily molded or otherwise shaped into the desired form. In order to increase the compactness of the device the upper base is provided with suitable conductor grooves leading to the binding posts on the lower base.

While I have described one embodiment of my invention herein it is to be understood that the same is susceptible of modification.

What I claim as new and desire to secure by Letters Patent of the United States is:

1. In combination, a base having flat vertical sides, a snap switch mechanism carried thereby, contacts for said switch mechanism, a threaded conducting shell carried on one face of said base, a conducting plate clamping said shell to said base, and terminal members for said switch mechanism carried upon the vertical sides of said base, one of said terminal connections being integral with said conducting plate and the other being directly connected to one of said switch contacts.

2. In an electric switch, the combination of a horizontally divided two-part base having flat vertical sides, means for holding the parts of said base together, a snap switch mechanism carried between the parts of said base, terminal plates fixed to the bottom of one part of said base and having integral extensions upon the flat vertical sides of said base, and binding screws carried by said extensions.

3. In combination, a horizontally divided two-part base, one of the parts of said base having vertically extending conductor grooves, while the other part of said base is provided with flat vertical sides, a switch mechanism housed between the parts of said base, contacts therefor carried upon one of the parts of said base, and terminal plates fixed to the bottom of said part of the base and having integral extensions resting upon the flat vertical sides of said part opposite the ends of the conductor grooves in the other part of said base.

4. In a lamp socket, in combination, an insulating base, a screw shell carried on the outer face thereof, a center contact for said shell fixed marginally on the outer face of said base, said shell having an inturned

flange overlapping a portion of said contact, an insulating disk interposed between said flange and said contact overlapped thereby, and conductor terminals for said contact and said shell arranged on the sides of said base.

5. In a lamp socket, in combination, a circular insulating base, a screw shell contact and a center contact therefor mounted on the outer face of said base, conductor terminals for said contacts on opposite sides of said base, a switch mechanism mounted on the inner face of said base and arranged to control circuit between one of said conductor terminals and its associated contact, said mechanism having an exposed conducting part on the outer face of said base overlapping a portion of said contact in the other circuit branch, and an insulating member interposed between said last mentioned contact and said conducting part overlapped thereby.

6. In a lamp socket, in combination, a circular insulating base, a threaded conducting shell carried on the outer face thereof, a center contact for said shell fixed to said base, conductor terminals for said shell and said contact, a switch mechanism carried by said base and arranged to control circuit between said center contact and the terminal thereof, said mechanism having a conducting part adjacent said shell, an insulating member interposed between said conducting part and said shell adjacent thereto, and means for securing said shell to said base, said means also clamping said insulating member against displacement.

7. In combination, a transversely divided two-part insulating base having a substantially closed chamber and aligned apertures in opposite side walls, a snap switch mechanism mounted on one of the parts of said base within said chamber and having a reciprocating operating member extending through said apertures, a terminal for said switch mechanism secured to the outer face of one part of said base and having a depending centrally disposed contact portion, a threaded lamp shell having an apertured flange carried on the outer face of said last mentioned part of said base, an annular insulating disk interposed between said flange and said base, and means extending through the parts of said base, said disk and said flange for securing all of the same together.

In witness whereof, I have hereunto subscribed my name in the presence of two witnesses.

CHARLES J. KLEIN.
